TOWEL DISPENSER CABINET

J. C. Layton, La Habra, and Council A. Tucker, Glendale, Calif., assignors to Towlsaver, Inc., Los Angeles, Calif., a corporation of California

Filed Oct. 2, 1959, Ser. No. 57,780

Term of patent 14 years

(Cl. D4—3)

FIG. 1.

FIG. 2.

FIG. 3.

FIG. 4.

FIG. 1 is a front perspective view taken from the right side of a towel dispenser cabinet showing our new design;

FIG. 2 is a top plan view thereof;

FIG. 3 is a bottom perspective view thereof; and

FIG. 4 is a left side elevational view thereof.

The dominant features of our design reside in the portions shown in full lines.

We claim:

The ornamental design for a towel dispenser cabinet, as shown and described.
